UNITED STATES PATENT OFFICE.

HAROLD D. ARNOLD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

VACUUM-TUBE CIRCUITS.

1,403,475.

Specification of Letters Patent. Patented Jan. 17, 1922.

Original application filed September 3, 1915, Serial No. 48,873. Divided and this application filed November 11, 1920. Serial No. 423,259.

To all whom it may concern:

Be it known that I, HAROLD DE F. ARNOLD, a citizen of the United States, residing at Maplewood, in the county of Essex, State 5 of New Jersey, have invented certain new and useful Improvements in Vacuum-Tube Circuits, of which the following is a full, clear, concise, and exact description.

This invention relates to vacuum tube 10 circuits and particularly circuits of the type in which a plurality of vacuum tubes are arranged in tandem.

The object of the invention is to provide an improved circuit connection between 15 vacuum tubes whereby fluctuations of current in the output circuit of one vacuum tube may be impressed on the input circuit of another vacuum tube.

In accordance with this invention, the out- 20 put circuit of a vacuum tube is provided with a path for direct current comprising an impedance, preferably a resistance and the input circuit of the succeeding tube is connected across a portion of the direct cur- 25 rent path containing said impedance. A condenser is placed between the direct cur- rent circuit and the second tube to prevent the flow of direct current, and a direct con- nection is also made between the input elec- 30 trodes of the second tube so that a normal potential difference may be applied there- between.

This type of connection is also useful for connecting circuits of various kinds either 35 with the input terminals or the output terminals of a vacuum tube.

The invention further resides in the specific details of the circuit hereinafter to be described, and shown in the accompanying 40 drawing, in which the figure represents, schematically, a circuit embodying the invention.

The subject matter of this application is divided out of application Serial No. 48,873, 45 filed September 3, 1915, for radio communica- tion.

Reference numerals are used in this appli- cation corresponding to those used in the ap- plication above referred to.

50 This application is a continuation in part of my application Serial No. 247,422, filed

July 30, 1918, now Patent No. 1,329,283, dated January 27, 1920.

Coil 13, which may be connected to any suitable circuit upon which electric impulses 55 may be impressed is inductively connected with the tuned circuit comprising coil 19 and condenser 20. Across the terminals of condenser 20, is connected the input cir- cuit of a detecting device which comprises 60 vacuum tube 21, condenser 22 and resistance 23. For the detection of modulated high frequency signals the purpose of the combination of the condenser and high re- sistance in connection with vacuum tube 21 65 is as follows—when a positive charge, for example, is forced upon the grid 9 of ele- ment 21, this charge is neutralized by elec- trons from the filament 8. Then, when a negative charge is forced upon the grid by 70 the incoming wave, this charge adds to that already present and produces a still larger negative charge upon the grid, since the negative charge cannot be neutralized by the electron stream. The condenser, therefore, 75 aids in decreasing the average current in the output circuit. The grid must, however, be conductively connected to the incoming circuit, otherwise the accumulated negative charge would remain and prevent further 80 operation. To provide for this, a high re- sistance leakage path 23 is shunted around 85 the condenser 22 to allow a leak, slow com- pared with the period of high frequency currents, but still rapid enough to permit considerable leakage in a time comparable with a period of telephonic waves.

The output circuit of this vacuum tube is supplied with current by battery 27 com- 90 ing through choke coil 28 and resistance 25, to the anode 10 condenser 24 serving as a high frequency shunt and condenser 26 to limit the direct current to the detector cir- cuit. The amplifier tube 31 has a battery 30 in series with its grid with resistance 29 95 across its input circuit. The output circuit of amplifier 31 comprises a battery 34 and choke coil 35, both shunted by condenser 33, and a coil 32. Coil 32 is inductively as- sociated with coil 36 may be connected to 100 any suitable circuit for the utilization of the amplified currents.

While a circuit has been shown which is especially adapted for the detection and amplification of modulated high frequency currents, it is obvious that the features of the circuit relating to the object of this invention are adapted for use in repeating electrical impulses of other forms.

What is claimed is:

1. In combination, a vacuum tube having 10 output electrodes, a path comprising a source of direct current and an impedance connected to said electrodes, a second path comprising a condenser and the input electrodes of a second vacuum tube connected 15 across a portion of said first path containing said impedance, and means for applying a steady difference of potential between said input electrodes.
2. In combination, a vacuum tube having 20 output electrodes, a path comprising a source of direct current and a resistance connected to said electrodes, and a second path comprising a condenser and the input electrodes of a second vacuum tube connect- 25 ed across a portion of said first path containing said resistance, and means for applying a steady difference of potential between said input electrodes.
3. In combination, a vacuum tube having 30 output electrodes, a path comprising a source of direct current and an impedance connected to said electrodes, a second path comprising a condenser and the input electrodes of a second vacuum tube connected 35 across a portion of said first path containing said impedance, and a conductive path between the input electrodes of said second tube.
4. In combination, a vacuum tube having 40 output electrodes, a path comprising a source of direct current and a resistance connected to said electrodes, a second path comprising a condenser and the input electrodes of a second vacuum tube connected 45 across a portion of said first path containing said resistance, and a conductive path between the input electrodes of said second tube.
5. In combination, a vacuum tube having 50 output electrodes, a path comprising a source of direct current and a resistance connected to said electrodes, a second path comprising a condenser and the input electrodes of a second vacuum tube connected 55 across that portion of said first path comprising said resistance and said source of direct potential, and a conductive path between the input electrodes of said vacuum tube.
6. In combination, two vacuum tubes, a circuit connecting the output electrodes of one of said tubes to the input electrodes of the other of said tubes, said circuit comprising a series condenser and a shunt im- 65 pedance at each side of said condenser.

7. In combination, two vacuum tubes, a circuit connecting the output electrodes of one of said tubes to the input electrodes of the other of said tubes, said circuit comprising a series condenser and a shunt path 70 at each side of said condenser, each of said paths comprising a resistance.

8. In combination a circuit comprising a resistance and means for producing potential variations across said resistance, a vacuum tube having input electrodes, and connections for impressing said variations on said electrodes, said connections comprising a series condenser.

9. In combination, a circuit comprising a 80 resistance, a source of direct current and means for producing variations in said current, a vacuum tube having input electrodes, and connections for impressing said variations on said electrodes, said connections 85 comprising a series condenser.

10. In combination, a circuit comprising a resistance and means for producing potential variations across said resistance, a vacuum tube having input electrodes, connections for 90 impressing said variations on said electrodes, said connections comprising a series condenser, and a resistance shunt for said input electrodes.

11. In combination, a circuit for the re- 95 ception of modulated high frequency currents, a vacuum tube for detecting and amplifying said currents, said vacuum tube having an impedance in its output circuit, and a circuit connected substantially in 100 parallel with said impedance for impressing variations in the output circuit on another amplifier, said second circuit comprising a series condenser.

12. In combination, a circuit for the re- 105 ception of modulated high frequency currents, a vacuum tube for detecting and amplifying said currents, said vacuum tube having an impedance in its output circuit, a circuit connected substantially in parallel 110 with said impedance for impressing variations in the output circuit on another amplifier, said second circuit comprising a series condenser, and a shunt conductance.

13. A detector and amplifier of high fre- 115 quency currents having in its output circuit a source of direct current, an inductance and a resistance in series, an amplifier having its input circuit in parallel with said series circuit, and a path of low impedance having 120 one terminal in common with said circuits, and its other terminal connected between said resistance and said inductance.

14. A detector and amplifier of high frequency currents having in its output circuit 125 a source of current and an inductance, a translating device having an input circuit connected in parallel to a portion of said output circuit containing said inductance, and a path of low impedance to high fre-

quency current connected in parallel to a portion of said output circuit containing said inductance.

15. In combination, a vacuum tube having 5 output electrodes, a path for direct current comprising said output electrodes, a source of current and an impedance, and a path for alternating currents comprising a condenser

and a work circuit, said second path being in parallel to a portion of said first path 10 containing said impedance.

In witness whereof, I hereunto subscribe my name, this 5th day of November, A. D. 1920.

HAROLD D. ARNOLD.
